UNITED STATES PATENT OFFICE.

CARL H. HOFFSTETTER, OF ERIE, PENNSYLVANIA, ASSIGNOR TO ODIN STOVE MANUFACTURING COMPANY, OF ERIE, PENNSYLVANIA, A CORPORATION OF PENNSYLVANIA.

STOVE.

Application filed July 1, 1921. Serial No. 481,797.

To all whom it may concern:

Be it known that I, CARL H. HOFFSTETTER, a citizen of the United States, residing at Erie, in the county of Erie and State of Pennsylvania, have invented new and useful Improvements in Stoves, of which the following is a specification.

The stove is particularly designed with relation to one utilizing radiants which extend upwardly from the burner and which are heated from the burner flames. With these stoves it is desirable to form a backing that will both radiate the heat and also protect the rear of the stove. I have found that this may be accomplished by using heavy smooth asbestos board which is held in place by a metal support protecting the back by placing the support in front of the back of the stove.

20 The invention is illustrated in the accompanying drawing as follows:—

Fig. 1 is a front elevation of the stove.

Fig. 2 a section on the line 2—2 in Fig. 1.

25 Fig. 3 a section on the line 3—3 in Fig. 1.

Fig. 4 a section on the line 4—4 in Fig. 3.

The stove is formed with the sides 1 bent forwardly from a back 2, angle irons 1^a stiffening the corners. A top 3 is arranged over the sides and back. The burner 4 has rearwardly projecting lugs 5 which engage the back 2 and screws 6 extend through the back into the projections securing the burner in place. The usual mixer 7 is arranged on a pipe extending from the burner through the side 1. Radiants 8 rest on the burner, jet openings 9 opening into the radiants.

A metal back 10 is arranged to the rear of the burner projections 5 extending through this back so as to support it. The bottom 40 of the back is bent rearwardly and upwardly at 11 forming a closure along the bottom and to the rear and downwardly at the top forming a closure at 12. The ends of the metal back have the forward extensions 13 projecting forwardly at the sides of the end radiants and the side plates 14 of the stove face are secured to these extensions 13. Front plates 16 are provided over the ends 45 of the sides 14 and the sides 1 of the stove.

50 A facing 17 is arranged on the support 10 immediately to the rear of the radiants. This facing is formed of asbestos board, pre-

ferably white, so as to protect the metal back 10 from the direct heat of the radiants and to radiate heat from the radiants. This 55 board is bent forwardly at 18 along the extensions 13 and the extensions 13 are crimped over the edge of the board 18 and 19, thus securing the board in place and 60 finishing the edge.

Perforations 20 extend through the metal back 10 near its upper end and a deflecting cap 20 is hung over the front of the radiants by means of projections 22 which extend rearwardly over the top of the radiants into 65 the openings 20, the projections having the up-turned ends 23 so that the plate 21 may be hooked into the openings. The plate is closed at the top as clearly shown in Fig. 3 forming a deflector to deflect the gases 70 through an opening 24 at the upper end of the metal back 10. A pipe flue 25 extends from the back 2 and the gases passing into the space between the metal back 10 and the back escape through this flue. 75

It will be noted that the metal back extends downwardly along the rear face of the burner forming an efficient support for the burner, the asbestos board facing terminating at the upper face of the burner thus 80 bringing it into proper relation with the radiants and strengthening the structure.

What I claim as new is:—

1. In a stove, the combination of a burner; radiants extending upwardly from the burner; and a backing at the rear of the radiants comprising a metal back having a facing of asbestos board, the back extending forwardly at the sides of the end radiants and the board extending forwardly along the forwardly extending portion of the back. 85

2. In a stove, the combination of a burner; radiants extending upwardly from the burner; and a backing at the rear of the radiants comprising a metal back having a facing of asbestos board, the side edges of the metal back extending around and enclosing the edge of the facing. 95

3. In a stove, the combination of a burner; radiants extending upwardly from the burner; a backing at the rear of the radiants comprising a metal back having a facing of asbestos board; a stove back; projections from the burner extending through the 100

metal back against the backing; and means for securing the burner to the stove back.

4. In a stove, the combination of a burner; upwardly extending radiants on the burner; and a backing at the rear of the radiants comprising a metal back extending downwardly along the rear side of the burner

and a facing formed of asbestos board arranged on the metal back and terminating at the face of the burner.

In testimony whereof I have hereunto set my hand.

CARL H. HOFFSTETTER.
